CLAIM

The ornamental design for a machine for preparing hot chocolate and frothing milk, as shown and described.

DESCRIPTION

1. Part of an electric machine for preparing hot chocolate and frothing milk

FIG. 1.1 is a top plan view of the machine for preparing hot chocolate and frothing milk showing our new design;

FIG. 1.2 is a front elevation view thereof;

FIG. 1.3 is a top perspective view thereof; and

FIG. 1.4 is a bottom perspective view thereof.

The broken lines shown in the drawings are for illustrative purposes only and form no part of the claimed design.
